US0D1050897S

(12) **United States Design Patent** (10) **Patent No.:** **US D1,050,897 S**
(45) **Date of Patent:** **** Nov. 12, 2024**

(54) **PACKAGING CONTAINER**

(71) Applicant: **ALBION CO., LTD.**, Tokyo (JP)

(72) Inventor: **Sayo Izuru**, Tokyo (JP)

(73) Assignee: **ALBION CO., LTD.**, Tokyo (JP)

(**) Term: **15 Years**

(21) Appl. No.: **29/851,756**

(22) Filed: **Aug. 31, 2022**

(30) **Foreign Application Priority Data**

Mar. 1, 2022 (JP) ..... 2022-004169 D

(51) **LOC (14) Cl.** **09-07**

(52) **U.S. Cl.** ..... **USPC** **D9/504**

(58) **Field of Classification Search**

USPC D9/575, 558, 516, 537, 539, 549-552, D9/560, 574, 540, 529, 690, 686, D9/500-505; D28/7, 76; D23/211.1, D23/211.2, 211, 225; D3/202; D7/509-511, 608; D4/114

(57) **CLAIM**

The ornamental design for a packaging container as shown.

DESCRIPTION

FIG. 1 is a perspective view of a packaging container showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The faded-out area illustrates portions of the article that form no part of the claim. The broken lines represent the boundaries of the claim and form no part thereof.

1 Claim, 7 Drawing Sheets
